(57) **CLAIM**

I claim the ornamental design for a food container, as shown.

DESCRIPTION

FIG. 1 is a perspective view of a food container showing my new design with the bottom surface in an expanded position;
FIG. 2 is a top view thereof;

FIG. 3 is a bottom view thereof;
FIG. 4 is an end view thereof;
FIG. 5 is an end view thereof, opposite that shown in FIG. 4;
FIG. 6 is a side view thereof;
FIG. 7 is a side view of the food container of FIG. 1 thereof, opposite that shown in FIG. 6;
FIG. 8 is a perspective view of the tub portion of the food container with the bottom surface in an expanded position;
FIG. 9 is a top view thereof;
FIG. 10 is a bottom view thereof;
FIG. 11 is an end view thereof;
FIG. 12 is an end view thereof, opposite that shown in FIG. 11;
FIG. 13 is a side view thereof;
FIG. 14 is a side view thereof, opposite that shown in FIG. 13;
FIG. 15 is a top view of the lid portion of the food container of FIG. 1;
FIG. 16 is a bottom view thereof;
FIG. 17 is an end view thereof;
FIG. 18 is an end view thereof, opposite that shown in FIG. 17;
FIG. 19 is a side view thereof;
FIG. 20 is a side view thereof, opposite that shown in FIG. 19;
FIG. 21 is an end view of the food container of FIG. 1, showing the bottom surface in a collapsed position;
FIG. 22 is an end view thereof, opposite that shown in FIG. 21, showing the bottom surface in a collapsed position;
FIG. 23 is a side view of the food container of FIG. 1, showing the bottom surface in a collapsed position; and,
FIG. 24 is a side view thereof, opposite that shown in FIG. 23, showing the bottom surface in a collapsed position.
The broken lines shown are for illustrative purposes only and form no part of the claimed design.
